UNITED STATES PATENT OFFICE.

AUGUSTUS P. MILLER, OF BALTIMORE, MARYLAND, ASSIGNOR OF ONE-HALF TO CHARLES PHILIP LAURENSEN, OF TOWSON, MARYLAND.

DEVICE FOR CARRYING OFF CINDERS AND SMOKE.

SPECIFICATION forming part of Letters Patent No. 602,865, dated April 26, 1898.

Application filed October 8, 1897. Serial No. 654,496. (No model.)

To all whom it may concern:

Be it known that I, AUGUSTUS P. MILLER, a citizen of the United States, residing at Baltimore, in the State of Maryland, have invented

5 certain new and useful Improvements in Devices for Carrying off Cinders and Smoke; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My invention relates to devices for carrying off cinders, sparks, and smoke from the smoke-stack of a locomotive, and has for its object to provide a device which shall be simple, cheap, and efficient; and it consists in 20 the construction and combination of parts of the same, as will be hereinafter more particularly set forth.

In the accompanying drawings, in which the same reference-numeral indicates a corresponding part in each of the views in which it occurs, Figure 1 is a side elevation of a train of cars with my improvement applied thereto. Fig. 2 is a front view of a locomotive, showing the location of the lower part 30 of the attachment thereon. Fig. 3 is a longitudinal sectional view of the front portion of the conductor. Fig. 4 is a similar view of a connector. Fig. 5 is a view of the screen. Fig. 6 is a detail view of one of the conductors 8.

35 Referring more particularly to the drawings, 1 indicates the smoke-stack of an ordinary locomotive, to the top of which are secured a slight extension 2 and a flaring bell-mouth 3. Pivotal secured to the extension at the top of the smoke-stack is a gooseneck 4, the front end of which registers with the extension and bell-mouth when in its raised position, and the rear portion is bifurcated 40 and registers with two conduits 5 and 6, which communicate with the drawers or receptacle 7 at the sides of the locomotive. The rear portion of the gooseneck above the conduits is provided with an opening which registers 45 with the forward end of a conductor 8. Extending from the top of the conduits is a

guide 9, upon which the end of the gooseneck slides when lowered for the purpose of passing through tunnels and under bridges and similar places.

55 The upper ends of the conduits 5 and 6 are each provided with a bead or collar 10, which extends substantially half-way around it, so as to make a close joint with the gooseneck when it is raised into its operative position and prevent its lateral movement. A cord 11 extends from the cab of the engine to the rear end of the gooseneck and is provided with means for securing it in position, so as to hold the gooseneck up into the position shown 60 in Fig. 1 when desired. When it is desired to lower the gooseneck, the cord is loosened in the cab and the weight of the gooseneck will cause it to swing upon its hinge and let the rear end slide down the guide 9, which 65 will cause the upper portion of the gooseneck to sink down substantially even with the top of the conductor. In this manner whenever the train is to pass under a bridge or other structure against which the gooseneck would 70 come in contact and be destroyed the engineer simply loosens the cord 11 and permits the gooseneck to fall into its lower position. As soon as the obstruction has been passed a 75 pull upon the cord will raise the gooseneck 80 into its operative position.

The conductor 8 consists of a series of sheet-metal sections, each of substantially the length of the portion of the train to which it is connected, and said sections are joined together at their ends by means of a flexible connector 12, preferably of rubber or other yielding material, which will permit of a train passing around curves, coupling the cars, and other usages to which it will be subjected. 85 The connectors are separable for permitting the separation of the portions of the conductor in manipulating the train. To prevent injury from the hot substances passing through the conductor, the interior of each of 90 these connectors is preferably provided with a fireproof lining 13, as asbestos or other material, which will not be so readily affected by the heat. At suitable points along the conductor lateral branches or inlets 14 are 95 formed for the entrance of air to assist in the draft through the conductor. The sections 100

are supported upon the different parts of the train in any suitable manner—as, for instance, by standards 15, the upper ends of which are provided with bands or clasps 16 to engage 5 with the conductor. In this manner my invention may be easily applied to locomotives now in use at a very small cost and without materially changing the construction of the same.

10 In the front portion of the conductor is located a screen 17, which may be made in any suitable manner—as, for instance, of woven wire of any suitable mesh—to prevent the passage of the larger sparks and cinders, but 15 which will not prevent the passage of the smoke or lighter particles of dust. When the train is in motion, the draft of air into the bell-mouth and through the conductor will cause the products of combustion to be 20 carried back against the screen, and all particles that are too large to pass through will be stopped and will at once fall down through the conduits into the receptacle at the side of the locomotive, from which they may be 25 readily removed, while the smoke and the smaller particles will pass unobstructed through the conductor and be delivered at the rear train through a suitable outlet, thus avoiding any discomfort to the passengers.

30 When the train is standing still, the gooseneck may be lowered to prevent the draft from the fire-box of the locomotive. It is obvious that changes may be made in 35 the minor details of construction of invention, and therefore I reserve the right to such changes as will fall within the spirit of my invention.

Having thus described my invention, I claim—

1. The combination, with a locomotive 40 smoke-stack of a gooseneck pivotally secured thereto at its front end, a conductor, and two receptacles communicating with the rear portion of the gooseneck, substantially as set forth.

45 2. The combination, with the smoke-stack of a locomotive, of an extension and a gooseneck secured thereto, the extension being provided with a bell-mouth and the rear portion of the gooseneck being bifurcated, receptacles communicating with the bifurcations, and a conductor communicating with the gooseneck above the conduits and a screen in the conductor, adjacent to the gooseneck, substantially as set forth.

55 3. The combination, with the smoke-stack of a locomotive, of a gooseneck pivotally secured at its front end to the upper end thereof, the rear end of which is bifurcated, of a conduit communicating with each of the bifurcations, the upper end of each conduit being provided with a bead extending substantially half-way around, a receptacle at the end of each conduit, and a guide from the upper ends of said conduits for supporting the end 60 of the gooseneck, and a conductor, communicating with the gooseneck, substantially as set forth.

55 In testimony whereof I affix my signature in presence of two witnesses.

AUGUSTUS P. MILLER.
